UNITED STATES PATENT OFFICE.

JOSEF HILMAR, OF MAGDEBURG, GERMANY.

AUTOMATIC TRAMWAY-SWITCH.

SPECIFICATION forming part of Letters Patent No. 714,301, dated November 25, 1902.

Application filed June 16, 1902. Serial No. 112,009. (No model.)

To all whom it may concern:

Be it known that I, JOSEF HILMAR, a subject of the Emperor of Austria, residing at 8 Blumenthalstrasse, Magdeburg, Germany, 5 have invented a new and useful Improvement in Automatic Tramway-Switches, of which the following is a specification.

My invention relates to an innovation in a working arrangement for the points of tramway-switches; and its objects are to safely work the points by means of the car, even without being obliged to decrease the speed. This arrangement can be so safely situated that it can never be disturbed by the traffic 10 of other vehicles and is in its construction, as well as manner of fixing, a very cheap working arrangement. I attain these objects by the mechanism illustrated in the accompanying drawings, in which—

20 Figure 1 is a schematic representation of the switch with the new working arrangement; Fig. 2, the working arrangement itself from a top view. Fig. 3 is a vertical cross-section on the line $y-y$ of Fig. 2. The left 25 side shows the vertically-placed working wheel and the tongue, the right side a horizontally-placed working wheel, the tongue left away. The connecting-rod 1 is shown as a broken-off piece. Fig. 4 is a longitudinal 30 section of the fragment-piece with the tongue situated inside according to section on the line $x-x$ of Fig. 3.

Similar letters refer to similar parts throughout the several views.

35 The tramway-switch a , with its tongues b and the connecting-rod c , are known. In order to work the points of this switch, I place on the track at a distance of one or more lengths of a car before the switch-tongues 40 fragments of rail d , Figs. 2 to 4, which are not different on their surface from the surface of the other rails, and thus an uninterrupted line of rail is obtained. These fragments of rails are connected to the rails in 45 the usual way with fish-plates. The lower part of the rail-groove e in these parts of rail gradually sinks downward from one end f to a certain depth, then runs again horizontally g , and comes up at the other end h again to 50 the normal height of the rail-groove. In the deepest part g of the groove lies a tongue i , which can be pushed into a side opening k under the top of the rail. The tongue i is pivoted in this opening k and its other 55 end may swing horizontally. If the tongue

is moved toward the rail-groove, then one end remains in the opening while the point touches the opposite side of the deep rail-groove. Thus this deeper part of the rail-groove gradually becomes narrower. For one 60 working arrangement two fragments of rail are necessary—one in each rail. Both tongues i are connected with a rod l , that when one tongue recedes into the opening k this causes the other tongue to appear in the deep rail- 65 groove. The movement of these combined tongues is to be conveyed to the rail-switch by a suitable arrangement.

In the drawings I have, for example, shown a rod m , bent at both ends, lying in the middle of the rails. The bent ends catch into holes in their respective connecting-rods c . The side movement of the working tongues i takes place by putting in the line-groove any kind of arrangement which by spring- 70 pressure is pressed downward, slides on the sloping surface f into the deep rail-groove, and presses the tongue sidewise. According whether the right or left line-groove of this arrangement is introduced the switch $l m c$ 75 is thus moved. As an arrangement for this purpose the known downward-movable little wheels can be used, or rods o , with little rollers p , as shown in Fig. 3. This is not to be a part of my invention, which consists 80 only of the tongue lying under the rail-top swinging in the deepened rail-groove and its connection with the switch.

What I do claim as my invention, and desire to secure by Letters Patent, is— 90

1. In a working mechanism for tramway-switches two fragments of rail each having its line-groove deepened and a side opening, tongues pivoted in said opening and connected to both switch-tongues, all as and for the 95 purpose set forth.

2. In a working mechanism for tramway-switches, two fragments of rail each having its line-groove deepened and a side opening, a tongue pivoted in said opening, both tongues 100 connected by a rod catching a double lever in gear with the connecting-rod of the switch-tongues, as described and for the purpose set forth.

In witness whereof I have hereunto set my 105 hand in presence of two witnesses.

JOSEF HILMAR.
